Inventor:
Thomas H. Kingston,
by Edward F. Allen,
his Atty.

UNITED STATES PATENT OFFICE.

THOMAS H. KINGSTON, OF WEST SOMERVILLE, MASSACHUSETTS.

PUTLOG.

Application filed December 19, 1922. Serial No. 607,869.

To all whom it may concern:

Be it known that I, THOMAS H. KINGSTON, a citizen of the United States of America, and a resident of West Somerville, in the county of Middlesex and Commonwealth of Massachusetts, have invented certain new and useful Improvements in Putlogs, of which the following is a specification.

10 This invention relates to putlogs such as are commonly used in erecting temporary scaffolding or staging when work is being done on brick or masonry walls.

15 It is an object of the invention to produce a putlog having the required strength and durability, yet simple in structure and easily manipulated.

20 It is a further object of the invention to combine with the above qualities, another one of safety in use, and to this end, the anchor plate is so arranged as to be temporarily secured to the wall by the cement or other binding material used, which without special effort on the part of the work- 25 man, finds its way to the anchor plate, and lodges about it in such manner that when it hardens an effectual securing means is provided.

30 Another object of the invention is to so shape the anchor plate that it may be readily adjusted for use, and when its service for the particular work has ended, it may be readily dislodged from its temporary security without undue effort or exertion on the part of the user.

35 Heretofore putlogs have been used wherein the anchor plate had a depending hook or lug, which was adapted to engage the inner side of the brick, or stone, upon which 40 the plate rested; such as shown in patent granted to me November 4, 1913, No. 1,077,839. This device has been widely used with great success, but instances have been noted wherein difficulty has been met in 45 dislodging the anchor plate from its seat without breaking off the hook or defacing the brick or stone in an effort to free the hook, so that the plate may be withdrawn.

50 It is an object of the present invention to dispense with such lugs or hooks because of the above mentioned reason, and to provide a plate which is so shaped as to be temporarily locked in place by the hardening 55 of the binding material which falls thereon during the process of laying the next tier of brick or stone above it.

The present invention further provides a plate of such construction, that intentional dislodgment thereof is greatly facilitated by a lifting and lowering movement of the outer end of the putlog, which rocks the plate, causing it to loosen the binding material, previously holding it in place, so that the putlog may be removed from its operative position by one hand of the work- 65 man.

The invention further consists in certain features of construction and arrangement which will be fully understood from a description of the drawings and the claims 70 hereinafter given.

Of the drawings:

Figure 1 represents in top plan view a portion of a brick wall in course of construction, showing a well known type of 75 scaffolding in which the present invention is included.

Figure 2—a perspective view showing the means of supporting the outer ends of the putlogs. 80

Figure 3—a part side elevation of a putlog shown in operative position.

Figure 4—a view showing the inner end of the putlog in a position it may be made to assume when the log is to be removed 85 from the wall.

Figure 5—a part top plan view of the anchor plate end of the putlog shown in Figure 3.

Like characters represent like parts 90 throughout the several figures of the drawing.

The putlog 10 shown herein made preferably of wood or equally strong but light material, has a slot 11 at the left end thereof to receive a blade like plate 12, having an extension 13 which will be hereinafter referred to as an anchor plate. 95

The said plate 12, being suitably secured in said log 10, as for instance by the rivets 100 14 and 15, the latter of which pass through a U shaped reinforcing stirrup, 14*, which has the additional rivets 15* securing it to the log.

In practise, the stirrup will be positioned in such manner, that when the log is tilted as in Figure 4, it will not contact with the wall, but the end of the log may be, if desired, fulcrumed on the wall as an aid in dislodging the plate 13. 105

The plate 13 is of novel construction, having a rocker like lower edge 16, and adapt-

ed to contact with the brick upon which it rests at approximately one point, in such manner that if need be it may be rocked, its upper edge 17 having considerable sheer, 5 the said edges terminating in a beak 18.

In practise, the extreme width of the plate is preferably slightly less than the distance between the brick courses, and its thickness is such as to ensure strength and 10 yet freely enter or be withdrawn from the usual width crevice formed between bricks or stones in the erection of a wall or the like.

In applying the putlog to use, the anchor 15 plate will be placed in a crevice most convenient for the purpose, in the then last course of brick or stone, with the log 10 resting on the usual ledger board 19, fast with the upright 20, to which the said log 20 is preferably secured by a spike or other means 21.

The next course of brick or stone will now be laid, during which operation, the binding material used will find its way into the 25 plate occupied crevice, either by design or incidental to the operation, in sufficient quantity to form a somewhat wedge shaped stop means between the end of the beak 18, and the outer surface of the brick as indicated at 22, see Figure 3.

More or less of the binding material will find its way to the points 23 and 24 but it is not essential that this shall occur, although it is preferable. As this binding material 35 requires but a short time in which to set, it will be readily seen that an effective lock has been formed which is capable of resisting ordinary efforts to dislodge the plate 13, particularly when said efforts are exerted in 40 the direction of length of the putlog.

In the dismantling process, the workmen engaged therein are placed at a disadvantage when the removal of the putlogs takes place. The footing afforded is meagre, 45 consisting of the ledger board, and consequently one hand is used in holding on to the upright, while with the other, the putlog must be dislodged from its resting place.

It is at this time that the novel shape of 50 the anchor plate, particularly its adaptability to be rocked, lends its aid to the workman.

The log may be grasped by the free hand at any convenient place adjacent the end 55 thereof, and lifted slightly and lowered again; these operations being repeated a number of times, or sufficiently to loosen the now hardened binding material so as to break its plate locking effect and enable the 60 plate to be removed from the crevice.

Ordinarily the above movements will suffice to loosen the plate so that it may be withdrawn, but if not, the log may be raised sufficiently to abut the wall where it will be 65 fulcrumed, thereby adding effective leverage

to assist in starting the plate from its resting place in the crevice.

It is obvious that the shape of the plate 13 may be changed so long as its top and bottom edges are so arranged as to permit 70 the plate to be rocked, and so long as the top edge is so shaped as to form a depression into which binding material will find lodgment, to thereby prevent the portion of said plate beyond said material from passing 75 said material when set, whereby a lock for said putlog is provided.

The preferred form however is as shown, as it offers an opportunity for the plate to 80 free itself in the event that all the material of the wedge 22 did not become broken away or loosened from the brick above.

It will be understood that this invention is equally applicable to the type of putlog 85 shown and described in the aforementioned patent, an indication of which is shown in Figure 1 of the drawing herewith.

Having described the invention I claim:

1. A putlog having a thin metallic extension 90 permanently secured thereto and adapted to be received in a crevice between adjacent building elements, and to be rocked in unison with said log for the purpose of releasing it from a crevice, one edge of said extension being curved to form a rocker, and another edge having an appreciable sheer terminating abruptly at the end of the said putlog, said edges converging toward the free end of said extension thereby forming a beak having angular relation to the main body of said extension, whereby an anchor is provided, adapted to coact with binding material to retain said putlog in position against outward longitudinal movement, the end of said putlog adjacent said extension being so arranged with respect to the said extension as to fulcrum on the face of a wall when said putlog and extension are to be rocked to disengage said extension from a crevice.

2. A putlog comprising a bar having a relatively thin metallic wall engaging member 115 permanently secured thereto at one end thereof, said member extending from a confining slot formed in said bar at the lower edge thereof in such manner as to provide a wall engaging fulcrum above said member for use when disengaging said member from a wall, the extending portion of said member being adapted to be received in a crevice between adjacent building elements, the lower edge of said member being defined by a compound curve whereby it may be rocked to free itself from the said crevice, and to form a clearance between it and the front edge of the building element upon which it may rest to prevent contact therebetween, in combination with a ledger board 120 adapted to support the outer end of said 125

bar, and an upright to which said bar is adapted to be secured.

3. A putlog having an end adapted to be positioned in close proximity to the face of a wall and to at times fulcrum thereon, and an anchor member comprising a metallic plate fast to said putlog at the said end thereof and extending therefrom, and having its lower edge curved to form a rocker 10 and having an upwardly extending beak adapted to coact with binding material to retain said putlog in position against longitudinal outward movement, and being removable therefrom by rocking movements 15 of said putlog, and attached plate, whereby the end of said putlog may be fulcrumed on

the face of a wall to thereby aid in the removal of said plate.

4. A putlog having fast therewith a rocker shaped plate adapted to be received 20 in a crevice between adjacent building elements and to be retained therein against longitudinal outward movement by binding material, said putlog and attached plate being of an arrangement whereby upward 25 rocking movements thereof may cause said putlog to fulcrum against the face of a wall to thereby aid in the removal of said plate from its position in a crevice.

Signed by me at Boston, Mass., this 14th 30 day of December, 1922.

THOMAS H. KINGSTON.
